UNITED STATES PATENT OFFICE

OSCAR JANSEN, OF ST. LOUIS, MISSOURI

NOZZLE

Application filed September 23, 1930. Serial No. 484,970.

This invention relates to nozzles, and with regard to more specific features, to nozzles for preferably flexible tubes used for dispensing pastes, or the like.

Among the several objects of the invention may be noticed the provision of a nozzle, which, upon pressing a flexible tube in the usual manner for forcing out material, will automatically open for dispensing purposes; the provision of a device of the class described which automatically and completely closes and positively cuts off flow when such pressure ceases; the provision of a nozzle of this class adapted to prevent excessive delivery of material and adapted to deliver a strip of material having an optimum cross section; and the provision of a device of the class described which is simple in form and neat in appearance. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claim.

In the accompanying drawings, in which is illustrated one of various possible embodiments of the invention,

Fig. 1 is a plan view of an exemplary tooth paste tube showing the application of the invention, the figure showing a cap removed.

Fig. 2 is a cross section taken on line 2—2 of Fig. 1.

Fig. 3 is a view similar to Fig. 2 showing another form of the invention.

Fig. 4 is a view similar to Fig. 3, showing another form.

Fig. 5 is an enlarged view taken at right angles to the cross section shown in Fig. 4, said Fig. 5 being taken on line 5—5 of said Fig. 4.

Fig. 6 is a view similar to Fig. 5 but showing the nozzle in delivery condition;

Fig. 7 is a cross section taken on line 7—7 of Fig. 6 showing a cross section of delivered material; and,

Fig. 8 is a perspective view showing the

operation of the invention but omitting a showing of exuding material.

Similar reference characters indicate corresponding parts throughout the several views of the drawings.

Referring now more particularly to Fig. 1, there is illustrated at numeral 1 a cap portion of a compressible or flexible tube 3. The tube 3 is provided with a closed bottom seam 5 and is composed of lead or the like so that it may be manually compressed after having been filled to exude material therefrom. This class of tube is already known and further description herein is deemed to be unnecessary.

The top portion 1 of the tube 3 has an outlet 7 over which is threaded a cap 9, said cap 9 not being a necessary adjunct to the tube but a desirable feature for a temporary covering of the nozzle during shipment or the like.

Interiorly the outlet 7 is provided with a rubber or like bushing 11 having an inside flange 13 and an outside flange 15 for holding purposes. The bushing 11 is of such size and consistency that it may be introduced into the outlet 7 after the tube has been filled, its natural resiliency bringing it into the position shown. Rubber, for example, fulfills the requirement for resiliency. It is to be understood however that other materials or substitutes for rubber may be used and that the flanges may be made of harder rubber or other material to insure proper positioning and retention.

One of the features of the present invention is the formation in a diaphragm 17, comprising the end of the bushing 11, of an outlet 19 such as shown in the figures. The outlet 19 comprises an I or H shape (Fig. 1) which is formed preferably by entering a thin blade into the rubber or the like, said blade having a straight edge or the I or H shape. When the cut is made preferably no rubber or material is removed. Thus when the blade is withdrawn, the resilient material closes the opening to form an air-tight seal.

It will be seen that the shape of the slit or cut 19 under consideration results in there being formed a pair of oppositely disposed symmetrical flaps, or gates 21 formed by the

right angular cuts, 23, 25 and 27. The gates 21 are rendered flexible or hinged by the relieving action of the cuts 23 and 27. Thus they bend outwardly as shown in Figure 6 when interior pressure is engendered. At the same time these gates effect a definite cutting off action when the pressure is relieved, said action being due to the tendency of the resilient material to return to its original position. During the opening event the sideward slits 23, 27 bulge somewhat laterally (see Fig. 8).

In Fig. 3 is shown a form of the invention similar to that illustrated in Figs. 1 and 2, except that there is no provision made for a cap 9. It will be understood that cap 9 is not necessary and Fig. 3 illustrates this embodiment. The appearance of this form is desirable.

In Figs. 1 and 2 the cap 9 is only used for protecting the rubber tip during shipment and to prevent material from being exuded by accidental pressure of the tube 3. If the tube 3 is in an external cardboard or like container, there is less possibility of the accidental application of said external pressure and then the Fig. 3 form may be used.

In Fig. 4 is shown another form of the invention wherein numerals illustrating corresponding parts are the same as in the figures heretofore described. The primary difference between this modified form and those described above is that the rubber nozzle is not in the form of a bushing 11, but comprises an external tip 11a which may be affixed by suitable adhesive and/or threaded to the cap portion 1. The I or H shaped outlet is formed as heretofore described.

Fig. 5 shows in detail how the gate-portions 21 close in and touch one another at the slit or opening 25 to definitely close off the interior of the tube 3 from the exterior thereof.

Fig. 6 shows how, when pressure is applied interiorly by pressing the tube 3, the gates or flaps 21 are opened or pushed outwardly to produce exudation of the paste or the like within. It also shows in connection with Fig. 7 how said paste assumes a cross section in exuding which is of an I- or H-like shape. The advantage of this cross section is that it provides a full body of exuding material. It is not merely a single slit cut into the nozzle (see numeral 29, Fig. 7), the cross section of which exudes a ribbon of the material which is thin and tapering laterally to a knife edge. With a mere slit not enough of the material is exuded per unit of length. By relieving the slit 25, as by means of the lateral slits 23 and 27 there is affected a greater mass of exuded material per unit of length of exudation.

It will be understood that in Fig. 7 is shown at dotted lines 29, the manner in which the material would come out were the slit 25 not relieved by the slits 23 and 27.

A further advantage of the said cross-section shown is that the sides are raised or thickened as shown so as to prevent excessive curling back onto the nozzle itself. The symmetrical arrangement of the flaps 21 also contributes to this advantage.

Another advantage of the invention, speaking generally, is that material may be exuded, say, onto a tooth brush or the like, and as the stroke is finished, the nozzle may be applied to the brush to clean the nozzle, or, if the nozzle is not applied to the brush, it may readily be held under a stream of running water or dipped into water or otherwise easily wiped off.

From the above and from the drawings, it will be seen that one form of the invention includes in the combination thereof an H-shaped slit in a flexible diaphragm which has no re-entrant angle or the like for breaking the surface near the slit. This combination of the H-shaped slit with the smooth unbroken surface surrounding it results in advantageous reciprocable or cooperative functions. One of the advantages is that the H-shaped opening forces paste or the like further away from the surface without curling back upon it, and that the small amount that may curl back, is positioned against a smooth and unbroken surface with no re-entrant portions which, if they were present, could not easily be cleaned.

Reciprocally, the smooth and unbroken surface permits better hinging of the flaps of the H-shaped flap so that there is not so much local bending, as would be the case near an angular and/or re-entrant portion. Hence the flaps effect a stronger closing action with a resulting more definite cut-off effect.

The device is sanitary, inexpensive, neat in appearance and effective in operation.

In connection with Figs. 1 to 3 the following points should be noted: The distance between the flanges 13 and 15 and the bushing 11 may be made slightly shorter than the corresponding faces of the outlet 7 with which they contact. Thus when the bushing is slipped into place, and the flanges 13 and 15 go into position, said bushing 11 is slightly stretched. This produces a cramping action on the upper flange 15. This cramping action induces a radial compression which insures that the walls of the slits 23, 25 and 27 will definitely press into one another to insure a definite closing action, even when the heavier mixtures of paste or the like are used. An advantage of the forms of the invention shown in Figs. 1-3 is that they present a neat appearance.

Fig. 8 shows the open position of the slits 21 without illustrating the exudation of material therefrom and illustrates the positions of parts when interior pressure is engendered.

If the advantages of a thick cross section at X is desired (Fig. 7) without the portions Y

(the thin material section 29 to be avoided), the sides of the flaps 21 may be joined with the edges of the slits 23, 27 by a thin membrane of rubber or the like, thus permitting the 5 complete and effective movement of the flaps 21 without paste exuding from the slits 23, 27. Or, the walls of the diaphragm 17 may be thickened at the slits 23, 27 to maintain contact with the sides of the flaps 21 as they move, 10 or, the interiors of the flaps themselves may be made thicker to accomplish the same result inversely. The advantages of a thick exudation are still had under these conditions, only the shape being changed.

15 In view of the above, it will be seen that the several objects of the invention are achieved and other advantageous results attained.

20 As many changes could be made in carrying out the above constructions without departing from the scope of the invention, it is intended that all matter contained in the above description or shown in the accompanying drawings shall be interpreted as illustrative and not in a limiting sense.

25 I claim:

30 A nozzle for exuding outlets of flexible tubes and the like comprising an enclosing diaphragm, said diaphragm covering over the mouth of the tube and forming a sanitary, smooth and unbroken exterior surface over the area which the contents of the tube reach upon exudation, said diaphragm having a hinge-forming, H-shaped slit therein, said 35 H-shape being adapted to reduce to a minimum the extent of the smooth and unbroken surface necessary, and said unbroken surface presenting optimum conditions for hinging operation of the slit.

40 In testimony whereof, I have signed my name to this specification this 27th day of September, 1930.

OSCAR JANSSEN.
